UNITED STATES PATENT OFFICE.

THOMAS CLARENCE RHODES, OF SHREVEPORT, LOUISIANA.

NON-REFILLABLE BOTTLE.

SPECIFICATION forming part of Letters Patent No. 761,543, dated May 31, 1904.

Application filed February 12, 1904. Serial No. 193,270. (No model.)

To all whom it may concern:

Be it known that I, THOMAS CLARENCE RHODES, residing at Shreveport, in the parish of Caddo and State of Louisiana, have invented 5 a new and Improved Non-Refillable Bottle, of which the following is a specification.

My invention relates to that class of non-refillable bottles in which an automatically-operating valve mechanism is placed within 10 the neck of the bottle after it has been filled and which will readily permit of the contents of the bottle being poured out, but will prevent the entrance of liquid to the bottle after it has been emptied.

Again, my invention generally consists of a valve-casing formed for convenience of manufacture in two sections and having a plurality of valve-seats and a valve-stem guide formed integrally therewith and a valve member held to operate within the casing and stem-guide and to seat upon a valve held to operate within and movable in the stem-guide and adapted to coöperate with the valve-seats.

My invention also seeks to provide a device 25 of this character of a simple, economical, and convenient construction which will readily serve its intended purpose.

With other objects in view, which will hereinafter be made apparent, my invention consists in certain novel constructions and combination of parts, all of which will be first described in detail and then specifically pointed out in the appended claims, reference being had to the accompanying drawings, in 35 which—

Figure 1 is a longitudinal section of a bottle with my invention applied. Fig. 2 is a similar view thereof, showing the bottle in its pouring position. Fig. 3 is a cross-section 40 taken practically on the line 3 3 of Fig. 1. Figs. 4 and 5 are similar views taken on lines 4 4 and 5 5, respectively, of Fig. 1. Fig. 6 is a detail perspective view of the valve-casing, the parts being shown separated; and Fig. 7 45 is a similar view of the valve.

In the drawings, in which like numerals and letters of reference indicate like parts in all of the figures, B designates the body, having the usual neck b and constructed of any suit-

able material. The neck b, where it is joined 50 with the bottle-body, is formed with an internal shoulder or seat b', and in the preferred form of my invention the neck b terminates in the threaded portion b², adapted to receive the cap or cover C, hereinafter referred to, 55 and the said neck b has a plurality of recesses for a purpose presently to appear.

The valve-casing 1 is fitted within the neck b of the bottle B and seats upon the shoulder b', as clearly shown in Figs. 1 and 2 of the 60 drawings. Near the upper end of the valve-casing each section 1^a 1^b thereof is formed with a recess 1^c to receive the locking members 3, consisting of the angled pieces 3^a and the spring members 3^b, secured thereto, and 65 the said angled pieces when the casing 1 is in position in the bottle-neck are forced into and held within the recesses b³ of the bottle-neck with their lips 3^x projecting into the recesses 1^c of the casing 1, and thereby firmly securing 70 the valve-casing within the bottle-neck.

The lower portion of the casing 1 is formed with a valve-chamber 1^d, near the upper end of which is formed a valve-seat 1^e, upon which the upper cup-shaped portion 2^a of the valve 75 2 is adapted to seat. At the lower end of the valve-chamber 1^b and in close proximity to the shoulder b' the valve-casing is formed with a second valve-seat 1^g for coöperating with the valve portion 2^b of the valve 2.

Each section 1^a 1^b of the valve-casing is formed with interlocking ears 1^y 1^z, and about midway the ends thereof the casing 1 has a transverse groove 1^m, adapted to receive a band 4, of rubber, cork, or other suitable material, which will hold the sections 1^a 1^b together and which will also serve as a washer to prevent the liquid creeping up between the bottle-neck and the valve-casing by capillary action or otherwise.

While the band 4 will usually be sufficient to serve the purpose intended, yet I may whenever desirable cover the entire casing or a portion thereof with the cork or other suitable sheath 5, as shown.

The valve 2, hereinbefore referred to, comprises a stem 2^c, which is vertically slidable in the bearing 1ⁿ in the valve-chamber 1^d and

which carries at its upper end a valve portion 2^a, preferably cup-shaped and having a concaved upper surface 2^x, formed with a squared countersunk portion 2^e to receive the loosening-rod hereinafter again referred to. Near the lower end the valve 2 has a second valve portion 2^b, which co-operates with the valve-seat 1^e of the valve-casing 1, and each of the valve portions 2^a 2^b may be covered with a cork or other suitable sheathing to insure a tight fit of the said valve portions upon their respective valve-seats.

Projected within the bottle-body B from the lower valve portion 2^b is a continuation of 15 the stem 2^c, which is tapered, as shown. The valve-casing 1 has a pouring-aperture 1^p connecting with the valve-chamber 1^d.

So far as described it will be apparent that after the valve and casing are in position within 20 the bottle-neck the contents of the bottle may be readily poured out (see Fig. 2) and a refilling of the bottle precluded, since should any attempt to refill the bottle be made the liquid will act upon the cup-shaped portion 2^x 25 of the valve 2, which will force the valve to its seats.

After the bottle is filled and the valve mechanism has been placed in position in the neck I place a stopper S, having a stem s' and surrounded by a cork or other suitable covering c', within the upper portion of the bottle-neck, the stem s' projecting within the pouring-aperture of the valve-casing, and the said stem carries a coil-spring S', screwed to its lower 35 end, which when the stopper S is in position engages the valve 2 and positively holds it on its seat while the bottle is not in use.

The screw-cap C, before referred to, may be screwed onto the bottle-neck to hold the 40 stopper S in place. (See Fig. 1.)

Should for any reason the valve 2 become stuck and cling to its seats, as sometimes happens when the bottle or receptacle is used for containing syrup and other like substances, it 45 is only necessary to admit the rod, (see dotted lines, Fig. 2,) having a squared end to fit the squared aperture 2^e of the squared countersunk portion, in the valve portion 2^a, when the valve may be turned and loosened from its 50 seat.

While I have shown the bottle, the valve-casing, and the valve as constructed of glass, yet I desire it understood that I may use any other suitable material; and while I have 55 shown the valve as a solid member, yet I may make it of a hollow body, if it is desirable.

I desire it further understood that slight changes in the detailed construction and arrangement of parts may be made without departing from the invention and the appended 60 claims.

I am aware that non-refillable bottles having valve mechanism contained within their neck have hereinbefore been provided, and I do not 65 claim said idea broadly; but

What I claim, and desire to secure by Letters Patent, is—

1. A non - refillable bottle, comprising in combination with a bottle-neck, said neck having a seat at its lower end and recesses near 70 its upper or pouring end, a valve mechanism including a casing adapted to rest on said neck-seat within the bottle-neck, means carried by said casing co-operating with the recesses within the bottle-neck for locking said casing in position, said casing having a valve-chamber, and valve-seats, and having a pouring-aperture communicating therewith, a double valve held within said chamber, and means for holding said double valve to its 75 seats at predetermined times.

2. A non - refillable bottle, comprising in combination with a bottle-neck, said neck having a seat at its lower end and recesses near 80 its upper or pouring end, a valve mechanism including a casing adapted to rest on said neck-seat within the bottle-neck, means carried by said casing for co-operating with the recesses within the bottle-neck for locking said casing in position, said casing having a valve-chamber, and valve-seats, and having a pouring-aperture communicating therewith, a double valve held within said chamber, and means for holding said double valve to its 85 seats at predetermined times, said means including a stopper adapted to fit said bottle-neck and having a portion projecting into said pouring-aperture, and a spring secured to the end of the said projecting portion of the stopper and engaging said valve. 90

3. A non - refillable bottle, comprising in combination with a bottle-neck, having a seat, a two-part valve-casing held therein and upon said seat, means for locking the two parts of the casing together, and means for locking said valve-casing within the bottle-neck, said casing having a valve-chamber, a valve-seat near the outlet end of said chamber, a second valve-seat at the inlet end thereof, and a valve-stem guide held between said valve-seats, a valve having a stem held within said valve-chamber with its stem freely movable in the stem-guide, said valve also having a seat-engaging portion at one end and a second seat-engaging portion near the other end for co-operating with the 105 valve-seats of the casing, said casing also having a pouring-aperture for the purposes specified. 110

4. A non - refillable bottle, comprising in combination with a bottle B having a neck b and having recesses b³, and a seat b', a valve mechanism comprising a casing 1, having a valve-chamber 1^d, a valve-seat 1^e at the entrant end thereof, a valve-seat 1^e near the exit end thereof, and a valve-guide 1ⁿ between said 120 valve-seats, said casing having recesses 1^c above the valve-chamber, means co-operating with the recess 1^c b³ to lock said casing within the bottle-neck, said casing also having a pouring-aperture 1^p, a valve operable within said 125 130

chamber and having a valve-stem 2^c and valve-seat-engaging portions 2^a 2^b for coöperating with said valve-seats and valve-guide for the purposes specified.

- 5 5. A non - refillable bottle, comprising in combination with a bottle B having a neck b and having recesses b³ and a seat b', a valve mechanism comprising a casing 1, having a valve-chamber 1^a, a valve-seat 1^c at the entrant end thereof, a valve-seat 1^e near the exit end thereof, and a valve-guide 1ⁿ between said valve-seats, said casing having recesses 1^c above the valve-chamber, means coöperating with the said recess 1^c b³ to lock said casing 15 within the bottle-neck, said casing also having

a pouring-aperture 1^p, a valve operable within said valve-chamber and having a valve-stem 2^c and valved seat-engaging portions 2^a 2^b for coöperating with said valve seats and guide, a stopper S having a stem s and a spiral spring secured to said stem, said stopper and stem shaped to fit said bottle-neck, and said pouring-aperture with said spring in engagement with said valve to hold said valve to its seat, and a cap C, for the purposes specified. 20 25
